UNITED STATES PATENT OFFICE.

VIRGIL L. SMITH, OF CHICAGO, ILLINOIS, ASSIGNOR TO WESTERN ELECTRIC COMPANY,
INCORPORATED, OF NEW YORK, N. Y., A CORPORATION OF NEW YORK.

TELEPHONE-TRANSFORMER.

1,339,793.

Specification of Letters Patent. Patented May 11, 1920.

Application filed March 1, 1917. Serial No. 151,722.

To all whom it may concern:

Be it known that I, VIRGIL L. SMITH, a citizen of the United States, residing at Chicago, in the county of Cook and State of Illinois, have invented certain new and useful Improvements in Telephone-Transformers, of which the following is a full, clear, concise, and exact description.

This invention relates to telephone transformers, and is particularly useful in connection with phantom repeating coils, duplex auto-transformers and similar transformers used in telephone circuits.

In such devices it is essential, in order to reduce to a minimum the injurious characteristic known as "cross-talk," that the so-called "phantom" windings be as closely balanced as possible with reference to their ohmic resistance, capacity and inductance; or, in other words said windings must be as nearly as possible in ohmic, electrostatic and electromagnetic balance. It is not a difficult matter to balance the phantom windings as to their ohmic resistance, as is well understood by those skilled in this art. In spite, however, of the greatest care in manufacture, the phantom windings may be unbalanced electrostatically and electromagnetically, and unless these unbalanced characteristics happen to equalize one another, the transformer may be unfit for use by reason of the cross-talk which it would introduce into the circuit.

The general object of the invention is to provide, in a device of the kind mentioned, means for assisting in the satisfactory balancing of the phantom windings, in order to reduce to a minimum the injurious characteristic known as "cross-talk."

In general, the invention is characterized by a supplementary winding or coil connected in series with one of the phantom windings and arranged in mutually inductive relation to the windings of the transformer. This supplementary winding has substantially no effect upon the electrostatic balance of any of the windings. It has, however, an effect upon the inductance of the phantom windings, this effect being greater upon the phantom winding with which it is connected in series than on the other phantom winding, and may so vary these inductances that the resultant electrostatic and electromagnetic balance of the phantom windings is improved.

The invention will be understood from the following description taken in connection with the accompanying drawing, in which Figure 1 is a perspective view of a phantom repeating coil having one form of the invention embodied therein, and Fig. 2 is a similar view showing another form in which the invention may be embodied.

Figs. 1 and 2 show phantom repeating coils in the condition in which they are tested before being potted. A tape-wound coil is shown at 3, from which project the ends 4, 5, 6 and 7 of the phantom windings and the ends 8, 9, 10 and 11 of the non-phantom windings. Such repeating coils before pottting are tested for cross-talk in any suitable well-known manner, as by an arrangement of artificial lines. If, in testing such a coil, it is found that the phantom windings are so much unbalanced that an objectionable amount of cross-talk results, the phantom windings are first balanced in any well-known manner as to ohmic resistance. If the amount of cross-talk is still objectionably large, it can be further reduced by the employment of the characteristic feature of the present invention, which will now be described.

Fig. 1 shows a simple form in which the invention may be embodied. The loose end 8 of the wire 7, which is one of the terminals of the phantom windings, is shown extended along and partially looped around the tape-wound coil 3, and is secured by a band of tape 13 in the manner shown. The effect of this partial looping of the wire 7 around the coil is to vary the inductance of the winding 6-7, and thus the electromagnetic balance between the phantom windings 4-5 and 6-7. The position of the looped end of the wire 7 which will most nearly cause perfect balancing of the phantom windings and therefore give the least cross-talk in the circuits of the repeating coil, can easily be determined by moving the end of the wire 7 to different positions around the coil 3. When the most advantageous position is found, the looped end is secured in that position by the tape 13 or in any other suitable manner. The repeating coil can then be potted in the usual manner.

Fig. 2 shows a form of the invention which operates upon the same principle as the form shown in Fig. 1 but provides for

the introduction of more inductance into the circuit of one of the phantom windings and therefore for greater effects toward perfect balancing. In Fig. 2, instead of a 5 partial loop of the wire 7, the latter is given a few complete turns which can be secured in any position on the outside of the coil 3, where they will link with the leakage flux and introduce impedance into the circuit of 10 the phantom winding 6—7. It can easily be determined by experiment which side of the supplementary winding 14 should lie against coil 3, and also what the position of the supplementary winding 14 should be 15 in order to obtain the most perfect balance. It is a simple matter for the tester to make a few turns in either the wire 4 or the wire 7 and then move these turns around on the surface of the coil 3 until the cross-talk, due to the unbalanced condition of the 20 phantom windings 4—5 and 6—7, has decreased to the minimum value which it seems possible to obtain. When this position for the supplementary winding 14 has 25 been found, said winding can be secured in that location in any suitable manner as by a tape 15 extending around the coil 3.

In the appended claims, the expression "supplementary winding" is used to denote 30 both the looped end of the wire 7 shown in Fig. 1 and such an arrangement as that indicated by the winding 14 in Fig. 2, and all other equivalent arrangements, *i. e.*, those whose function it is to supplement the 35 action of one or more of the main windings of the coil and thereby to remove a lack of balance between the main windings and whose action is therefore subsidiary to the action of the main windings.

40 What is claimed is:

1. In a telephone transformer, a plurality of transformer windings, and a supplementary winding connected in series with one of said transformer windings and arranged 45 to link with the leakage flux from said transformer windings.

2. In a telephone transformer, a plurality

of transformer windings, and a supplementary winding connected in series with one of said transformer windings and arranged 50 to link only with the leakage flux from said transformer windings.

3. In a telephone transformer, a toroid comprising a plurality of transformer windings and a supplementary coil arranged 55 exteriorly of said toroid and adapted to link with the leakage flux from said transformer windings.

4. In a telephone transformer, a plurality of windings, a supplementary winding connected in series with one of said transformer windings, and means for securing 60 said supplementary winding in mutually inductive relation to said transformer windings at a point determined by trial where 65 the inductive effect of said supplementary winding will most nearly effect perfect electrostatic and electromagnetic balance of the windings of said transformer.

5. In a phantom repeating coil, a plurality 70 of repeating windings, including phantom windings, and means for assisting in the balancing of the phantom repeating windings comprising a supplementary winding connected in series with one of said 75 phantom windings and arranged to link with the leakage flux from the windings of the repeating coil.

6. A method of balancing the windings 80 of a telephone transformer which consists in providing one of the ends of one of the transformer windings with a supplementary winding, determining by trial the position relative to the transformer where the inductive effect on the transformer windings 85 of said supplementary winding will most nearly effect perfect electrostatic and electromagnetic balance of the transformer windings, and securing said supplementary winding in such position.

In witness whereof I hereunto subscribe my name this 26 day of Feb. A. D., 1917.

VIRGIL L. SMITH,
